SUPPORT FOR A HEARTH BROILER

William P. Fox, Brewster, Mass., assignor to Design Development Corporation, Brewster, Mass., a corporation of Massachusetts

Filed May 8, 1961, Ser. No. 65,069

Term of patent 14 years

(Cl. D81—10)

The figure is a view in perspective of a support for a hearth broiler showing my new design.

The broiler basket and lid therefor, shown in broken lines, are included for illustrative purposes only.

I claim:

The ornamental design for a support for a hearth broiler, as shown and described.
